Primary Examiner — Paula Greene(74) *Attorney, Agent, or Firm* — Fish & Richardson P.C.(57) **CLAIM**

The ornamental design for a handheld device, substantially as shown and described.

DESCRIPTION

FIG. 1 is a perspective front view of a first embodiment of a handheld device.

FIG. 2 is a front view of the embodiment of FIG. 1.

FIG. 3 is a rear view of the embodiment of FIG. 1.

FIG. 4 is a right side view of the embodiment of FIG. 1.

FIG. 5 is a left side view of the embodiment of FIG. 1.

FIG. 6 is a top view of the embodiment of FIG. 1.

FIG. 7 is a bottom view of the embodiment of FIG. 1; and, FIG. 8 is a perspective front view of a second embodiment of a handheld device.

The broken lines in each figure illustrate graphical environmental features that form no part of the claimed design.
